PURIFICATION OF TAR ACIDS

Carl E. Hartwig, Bayonne, N. J., assignor to The Barrett Company, New York, N. Y., a corporation of New Jersey

No Drawing. Application July 19, 1933, Serial No. 681,167

10 Claims. (Cl. 260—154)

This invention relates to the purification of tar acids and more particularly to a method for removing objectionable odor from tar acids and improving their color stability.

5 By "tar acids" as used in this specification, I mean the organic cyclic hydroxy compounds (for example phenol, the cresols, the xylenols) resulting from the destructive distillation of organic

matter, such as bituminous coal, which form salts with caustic soda and are capable of being extracted from solution in organic solvents by

means of aqueous caustic soda or other aqueous alkaline solutions. By "carbolate" or "carbolate solution" I mean the solution of reaction products obtained by treating free-tar acids or free-

tar-acid-bearing material with alkaline materials, especially caustic soda solution. Carbolate solutions contain as solute chiefly sodium (or other metal, e. g., potassium) salts of tar acids.

10 The term "tar acids" is used in the claims in a comprehensive sense and is intended to include tar acids whether free or in combination as metal salts.

It is customary to recover tar acids from tar- 25 acid-containing oils by treating such oils with an aqueous alkaline solution; these oils may be condensates obtained from the distillation of coal, tar or of other tar-acid-producing material.

Such oils, commonly called "carbolic oils" vary 30 widely in tar acid content, depending on their source. Carbolic oils resulting from by-product coke-oven operation ordinarily contain from 7 to 35 per cent by volume of tar acids, but wide variations from this range may occur. Caustic soda

35 is ordinarily employed for the extraction, although other alkaline materials such as caustic potash or their aqueous solutions may be employed. The solution of the sodium salts of tar acids (i. e., the carbolate solution) is separated

40 from the oil and preferably diluted with water and distilled with steam to remove neutral hydrocarbon material which dissolves in the caustic solution in appreciable amounts together with the tar acids. The tar-acid content of such

45 carbolate solutions will vary with completeness of extraction of the oil, strength of caustic solution used and other factors. Commercial car-

50 bolates, before distillation with steam, may contain tar acid salts equivalent to about 35 to 60 percent by volume of tar acids. Dilution and dis-

55 tillation with steam to remove neutral oil reduces the tar acid content, for example to about 20 percent by volume. The carbolate solution freed of neutral oil is treated with an acid such as sulfuric acid or with carbon dioxide, or with

an acid salt such as sodium acid sulfate, sodium bicarbonate or the like, to liberate the tar acids, which float as an oily layer on the aqueous salt solution resulting from the acid treatment. The crude acid layer is separated by decantation for rectification or storage as desired.

The acids produced in the ordinary way as above described readily darken on exposure to light and have an offensive odor, even when refined. These objectionable characteristics greatly lessen the value of the tar acids or make them worthless for many purposes.

It is an object of this invention to provide a process for refining tar acids which results in substantially complete removal of such objectionable odor and results in tar acids of improved color stability. The process of this invention may be carried out without seriously interfering with the ordinary routine of tar acid production.

In one method of carrying out my invention, I agitate the carbolate solution, preferably after dilution and removal of the neutral oil by steam distillation, with a small amount of a metal which will cause the evolution of hydrogen from alkaline solutions on contact with such solutions. I prefer to use from 0.25 per cent to 1 per cent by weight of metal based on the weight of tar acids treated, but may use up to 10 per cent or more. The mixture is maintained at a tem-

25 perature of from 70° to 90° C. during the reaction. Owing to appreciable hydrolysis of the sodium phenates carbolate solutions resulting from caustic soda extraction have a strong alkaline reaction. This is also true of the solutions of tar acids in other strong bases. Furthermore, the carbolate solutions commercially produced frequently contain a small excess of free caustic

30 soda. The alkalinity of the customary commercial carbolate solutions, whether or not containing an excess of free caustic soda, is sufficient to react with the small amounts of metal used in carrying out my process. I have found aluminum dust and zinc dust effective reagents in carrying out this process. I prefer to use zinc dust since

35 40 45 50 it is more effective. After agitating the carbolate with the metal for a short while, say for 15 minutes or longer and filtering, the tar acids may be recovered from the filtered solution by usual acidification.

As an alternative procedure a dilute solution of a mineral acid or of an acid salt may be added to crude or partly refined free tar acids, and the acidified tar acids agitated with a small amount

55 of a finely divided metal such as will cause the

evolution of hydrogen on contact with the mineral acid solutions. As in the first modification I may use amphoteric metals such as aluminum or zinc but prefer to use zinc. I may also use such metals as iron, nickel and tin to react with the acidified tar acids. The tar acids are preferably maintained at the boiling temperature of the reaction solution during the reaction. Upon the completion of the reaction the tar acids are separated by decantation or filtration from the aqueous layer, washed with water and distilled as usual. Where the use of mineral acids is not desirable, the crude tar acids, containing a small quantity of water, may be treated with powdered metallic magnesium or calcium instead of with the metals mentioned above, the magnesium reacting with the aqueous solution to evolve hydrogen.

The following are given as illustrative examples of the practice of this invention:

Example No. 1.—Carbolate solution, obtained by extracting coal tar carbolic oil with caustic soda, was freed from dissolved hydrocarbons and other non-acid impurities by diluting and distilling with steam to give a carbolate containing salts of tar acids equivalent to about 20 per cent by weight of tar acids based on the weight of solution; the carbolate consisted for the most part of a solution of the sodium salts of tar acids, the salts of phenol, the cresols and the xylenols predominating. To one liter of carbolate were added 2 grams of zinc dust, equivalent to 1 per cent by weight of the tar acid content of the carbolate. The mixture was well agitated for 30 minutes and the temperature maintained at approximately 90° C. for about 30 minutes. The carbolate solution was filtered and thus freed of solid matter, acidified and tar acids then separated and refined by distillation in vacuo.

Example No. 2.—To 200 grams crude tar acids were added 50 c. c. of a solution of 10 per cent sulfuric acid. This amount of acid was sufficient to dissolve completely the zinc dust used in the treatment. The acid formed an aqueous solution that readily settled out from the tar acids after the zinc treatment. One gram of zinc dust was added, equivalent to about 0.5 per cent by weight of the tar acids treated. The resultant mixture was boiled under a reflux condenser for at least 15 minutes or until the evolution of hydrogen had stopped, the boiling in this case furnishing sufficient agitation to effect the desired reaction. The tar acids were separated from the solid residue by filtration, washed with water and distilled in vacuo. The water-washing step is desirable to remove by-products of the reaction.

In my co-pending application Serial No. 631,275 I have disclosed a method for purifying and removing foreign objectionable odor from tar acids by treating their alkali and metal salt solutions with gelatinous metal hydroxides, preferably with iron hydroxide. In that application I have disclosed that it is desirable to agitate such a carbolate solution at a temperature of 50° to 90° C., with 1½ to 2 per cent or more of, for example, iron hydroxide, in order to improve the odor of the resultant tar acids. When desired, that method of purification may be combined with the process disclosed in this specification and more particularly with that modification described in Example 1, i. e., the carbolate may be agitated with a gelatinous metal compound to remove impurities and before or after the treatment with gelatinous metal, impurities may be removed by agitating the carbolate with a metal such as zinc

dust as herein disclosed. When such a combined process is carried out the iron or other metal hydroxides may be added to the carbolate solution after treatment of the carbolate with metal as described herein and before the filtration, thereby avoiding the necessity of double filtration and settling steps. Such a combined process may be employed when a highly purified tar acid is desired.

The tar acids obtained by my process are substantially free of disagreeable odor, are of improved color stability and are of enhanced value for many purposes. The improvement in odor and color stability of the tar acids resulting from my method appears to be based on complex reactions. It may be due to a reduction or hydrogenation of relatively minute quantities of highly unsaturated and reactive pyrogenetic compounds which possibly contain oxygen or sulfur or both.

When tar acids are treated with a metal (e. g., zinc) in acidified solution, as in the second example given above, the acid treatment and subsequent separation of the aqueous layer incidentally result in the removal of tar bases (if present) in the form of water-soluble salts; if insoluble salts are formed, they are removed in the filtration step. Since zinc salts are known to form addition compounds with tar bases, the use of zinc may help materially in the removal of the bases. Among the bases which may be present are pyridine, quinoline, their homologues, and similar nitrogenous compounds.

Without departing from the scope of my invention I may treat in the manner described above not only carbolate formed by extracting tar-acid-bearing oil but also carbolate formed by dissolving impure acids in caustic soda or other alkaline solutions or produced in any other way; free tar acids and solutions of free tar acids, whether the tar acids are produced by destructive distillation of coal, or by other methods.

It will be understood that the invention herein is not restricted to the embodiments disclosed, except as defined by the appended claims.

I claim:

1. The method of purifying tar acids which comprises mixing the tar acids with a free metal capable of evolving hydrogen on contact with an acid solution and agitating the resultant mixture.

2. The method of purifying tar acids which comprises treating a carbolate solution with a free metal capable of reacting with an aqueous hydroxide solution to cause the evolution of hydrogen.

3. In the purification of tar acids the step which comprises contacting a carbolate solution with a free amphoteric metal.

4. In the purification of tar acids the step which comprises treating a carbolate solution with zinc.

5. In the purification of tar acids the steps which comprise acidifying tar acids and treating the acidified tar acid with a metal capable of reacting with acid to liberate hydrogen.

6. In the purification of tar acids the step which comprises treating with metallic iron, tar acids acidified with a mineral acid.

7. In the purification of tar acids the step which comprises contacting an aqueous mixture containing tar acids with magnesium and agitating the resultant mixture.

8. The method of purifying tar acids which comprises contacting a carbolate solution with

5 a free metal capable of reacting with a sodium hydroxide solution to cause the evolution of hydrogen, contacting the carbolate solution with gelatinous metal hydroxide, separating the solution from solid residue, and liberating the tar acids from the solution.

10 9. The method of purifying tar acids which comprises contacting a carbolate solution with zinc, adding iron hydroxide to the resulting mixture, separating the resulting solution of carbo-

late from the solid residue, and acidifying the carbolate to liberate the tar acids.

10. The method of deodorizing tar acids and increasing their stability towards light which comprises acidifying tar acids with a mineral acid, treating the resulting mixture with metallic zinc, whereby tar bases are dissolved as salts in the aqueous phase and separating the tar acids from the aqueous phase.

CARL E. HARTWIG. 10
